UNITED STATES PATENT OFFICE

2,379,303

COMBINED CALL-INDICATOR, DIALER,
AND TIMER

Sidney Israel, Brooklyn, N. Y.

Application January 27, 1941, Serial No. 376,148

1 Claim. (Cl. 235—125)

This invention relates to a telephone call-indicator, dialer and timer for indicating the number of calls that have been transmitted over the telephone; also for dialing the telephone and timing the calls.

An object of this invention is to provide a portable device having a sight opening and means for keeping an accurate account of the number of calls transmitted over a telephone.

Another object of this invention is to provide combined means for actuating the said device as well as for actuating a dialing disk of a telephone.

Another object of this invention is to provide timing means integral with the call-counting and dialing device whereby the user will have a visual indication of the length of time that has elapsed since he started talking to the party called.

Another object of this invention is to provide in a device of the class described, a visual indication of the number of telephone calls already made, and a signal or click when the counting portion of the device registers an advance of one above the previously indicated number of calls made.

Another object of this invention is to employ ratchet teeth which will prevent rotation of the dialing mechanism in the wrong direction.

Another object of this invention is to provide a dialing knob having a substantially hook-shaped end portion adapted for positive engagement with the apertured portions of the dialing disk of a telephone.

With the above and other objects in view, the invention will be hereinafter more particularly described, and the combination and arrangement of parts will be shown in the accompanying drawing and pointed out in the claim which form part of this specification.

Reference will now be had to the drawing, wherein like numerals of reference designate corresponding parts throughout the several views, in which:

Figure 1 is a side elevation of the combined call-indicator and dialer.

Figure 2 is an end elevation of the device shown in Figure 1.

Figure 3 is a cross-sectional view, the section being taken as on line 3—3 in Figure 1.

Figure 4 is a cross-sectional view, the section being taken as on line 4—4 in Figure 3.

Figure 5 is a fragmentary end portion of the device, on an enlarged scale.

Figure 6 is a fragmentary dialing end portion of the device, on an enlarged scale.

Figure 7 is an end view of an end plug.

Figure 8 is a cross-sectional view of an end plug, the section being taken as on line 8—8 in Figure 6.

Figure 9 is a side elevation of a combined call-

indicator, dialer and timer, partly broken away to show the interior of the timer.

In the illustrated embodiment of the invention, the numeral 10 indicates a combined device comprising a tubular casing 11, preferably having a circular cross-section. One end of the casing 11 is closed by a plug 12 having a flange 13 which interlocks with the casing. The other end of the casing is closed by a cylindrical plug 14 which is slidable in the casing during the assembling of the device.

The plug 14 has a bifurcated portion 15, the forks of which have a transverse aperture 16 therethrough. The casing 11 has a through aperture 16' of the same diameter as the aperture 16. A spindle 18 journaled in the apertures 16 and 16' maintains the plug 14 and casing 11 in unitary relation. The forks 17, 17 also have a through transverse aperture 19 forming a bearing 20 for a pin 20.

The spindle 18 has a dialing knob 21 at one end thereof. The knob 21 has an end portion 22 with a substantially V-shaped peripheral groove 23 at its junction with the knob 21. The portion 22 is made of smaller diameter than the dialing apertures in the rotatable disks of telephones having dialing devices.

The plug 12 has a bifurcated portion 24, the forks 25 of which have two parallel apertures 26 therethrough. Pins 27 have been mounted in the apertures 26.

In assembled relation the pins 20, 27, 27, are in parallel relation with the spindle 18.

It is to be noted that the pins 20, 27, 27, are rotatably mounted respectively in the apertures 19, 26, 26. The overall length of the said pins is made of a size which will not hamper the free movement of the plugs 12 and 14 inside the casing 11.

A wheel 28 has been mounted on the spindle 18. The free end portion of the spindle 18 is of a size to permit free movement thereon of the wheel 28. At approximately the mid portion of the spindle 18 is a knurled surface 29 which is designed to come into fixed engagement with the apertured inner surface of the wheel 28 when driven into assembled relation.

An endless band 30, preferably made of elastic material, serving as a means for tensioning the band, has been mounted in frictional engagement on the wheel 28, on the pin 20, and on the pins 27, 27. The endless band 30 has numerals or other indicia imprinted thereon. When numerals are used they begin with "1" and end with "66" for a purpose to be described. The indicia identified by the numeral 31 are arranged in spaced apart relation, and preferably so as to read transversely of the length of the band.

The wheel 28 has ratchet teeth 32 in one of its plane surfaces. The teeth 32 are of a length

corresponding to the distance between the centers of successive numerals. The outer periphery of the wheel 28 has axial ribs 33 serving to grip the endless band 30.

A wire spring 34 suitably fixed in the plug 14 and having its free end in engagement with one of the ratchet teeth 32 permits rotation of the ratchet wheel 28 in only one direction. The user may thus grip the knob 21 and give a partial rotation to the wheel 28 and cause the endless band 30 to move step-by-step so as to bring successive numbers into view through a sight opening 35 in the casing 11. It is to be noted that when the user gives a partial rotation to the wheel 28, that the spring 34 which was seated at the lower elevation of a ratchet tooth is caused to rise to the top of the ratchet tooth and then drops. The spring then strikes the inclined wall of the succeeding tooth and on contact taking place, a click or sharp sound or audible signal results. This gives a positive warning to the user not to turn the dial any further when registering a single call.

When the device shown in Figures 1 to 8 inclusive is used for dialing telephones, the numbers on the endless band 30 may comprise the allowable number of calls per month to a subscriber, such as 66, as is the case in New York city. The user manipulates the dialing knob 21 every time a call is made so as to bring the successively higher number into view. The purpose of dividing the band into 66 equal divisions is to give a telephone user a positive check on the number of calls he has made or used up of the 66 allowable calls at any given day of the month.

The user, upon passing the 66 allowable calls, repeats the operation and then has a positive indication at a glance of the number of extra calls he has made.

It is to be noted that the free end face 36 of the dialing knob 21 is of convex form to facilitate insertion of the end portion 22 in the apertures of a dialing disk.

The spring 34 serving to prevent rotation of the dialing knob in the wrong direction is reinforced against bending by a stub pin 37 (Figure 8). This bending action would happen if the ratchet were forcibly turned in the wrong direction. The stub pin 37 prevents this bending action.

It is to be noted that the ratchet teeth are arranged to prevent accidental rotation of the knob 23 during its use as a dialing means.

As shown in Figure 9, I have provided a combined call-indicator, dialer and timer 40 for the purpose of giving a visual indication to the telephone user of the length of time that has elapsed since he started talking to the party called. As shown, the timer 41 comprises a transparent cylindrical container 42 preferably made of transparent plastic material and having a closed end 43, two annular contacting surfaces 44, 44, and an internal diameter larger than the outer diameter of the casing of a call-counter and dialer 10 so as to provide a storage space for a very fine granular material such as fine sand 45.

The timer 41 has an integral annular member 46 integrally thereof. The member 46 is angularly positioned and has two apertures 47, 47 on diametrically opposite points thereof, the said apertures providing connecting passageways between the substantially equally divided com-

partments 50, 50 in the timer and forming a time measuring device similar to an "hour glass." It is to be noted that the amount of sand and size of the connecting apertures are such that a given amount of time will be consumed in the passage of the sand from one compartment to another.

As shown in Figure 9, each of the compartments 50 will be provided with five graduations equally spaced apart, each one of which represents a minute. The purpose of these graduations is to give a visual indication of the passage of time during conversations over the telephone.

It is to be noted that one of the apertures 47 is positioned at the highest elevation of the member 46 and the other aperture 47 is positioned at the lowest elevation of said member.

Due to the large number of numerals required for telephone dialing, the numerals being imprinted so as to occupy the entire length of the band, the band is considerably longer than the permissible length of the casing, which has to be confined within the palm of the hand. As best shown in Figure 3, it will be seen that the band 30 is rotatably mounted in superposed parallel sections and in interfolded relation within the casing to permit all of the numerals 31 to be successively exposed in the sight opening 35.

It is to be noted that while I have shown the number counting device 10 as adapted for telephone dialing, that I may employ the said counting device wherever it is desired to keep a record of successively increasing units by mechanism which will operate only in one direction and which will give an audible signal for each advance. It is also to be noted that the device 10 having the hook-shaped dialing knob 21 may also be used solely for dialing telephones. It is also to be noted that the device 40 having the time measuring device 41, shown in Figure 9, may be used solely for measuring time.

In accordance with the patent statutes I have described and illustrated the preferred embodiment of my invention, but it will be understood that various changes and modifications can be made therein without departing from the spirit of the invention as defined by the appended claim.

I claim:

50. In a telephone call indicating device of the character described, a tubular casing having a sight opening, an endless and tensioned band having a large number of numerals imprinted thereon and causing said band to be considerably longer than said casing, said band being rotatably mounted in superposed parallel sections and in interfolded relation within said casing, to permit all of said numerals to be successively exposed in said opening, a spindle having an axially ribbed drive wheel for gripping said band, one 55 end of said spindle having grip means adapted for engagement by the user for actuating said band, ratchet teeth on said drive wheel, said ratchet teeth being positioned on one of the plane surfaces of said drive wheel, a spring engageable 60 with said teeth to permit rotation of said band in only one direction and to cause an audible signal for each successive numeral when moved by said ratchet teeth, and reinforcing means preventing movement of said movable devices in the 65 wrong direction.

SIDNEY ISRAEL.
